UNITED STATES PATENT OFFICE

115,021

DESIGN FOR A LABEL

Alberta M. Bourne, Douglas County, Nev.

Application March 6, 1939, Serial No. 83,387

Term of patent 14 years

To all whom it may concern:

Be it known that I, Alberta M. Bourne, a citizen of the United States and residing in the county of Douglas and State of Nevada, have invented a new, original, and ornamental Design for a Label, of which the following is a specification, reference being had to the accompanying drawing, forming a part thereof.

In the accompanying drawing, the figure is a plan view of the label.

I claim:

The ornamental design for a label, substantially as shown.

ALBERTA M. BOURNE.
